UNITED STATES PATENT OFFICE.

NOAH W. HOLT, OF BUFFALO, NEW YORK.

FEED MECHANISM FOR ROLLER-MILLS.

SPECIFICATION forming part of Letters Patent No. 288,808, dated November 20, 1883.

Application filed July 17, 1883. (No model.)

To all whom it may concern:

Be it known that I, NOAH W. HOLT, of the city of Buffalo, in the county of Erie and State of New York, have invented new and 5 useful Improvements in Feed Mechanism for Roller-Mills, of which the following is a specification.

This invention relates to an improvement in the construction of the mechanism whereby 10 the material is fed between the grinding or crushing rollers. Heretofore revolving feed-rollers have been most generally employed in roller-mills for feeding the material to the rollers; but it is found in practice that when the 15 material is of an adhesive or fuzzy character the feed-rollers fail to feed the material uniformly over the entire length of the crushing-rollers, whereby the operation of crushing or grinding is rendered irregular, and more or 20 less unsatisfactory.

The object of my invention is to construct a feed mechanism which will distribute the material over the entire length of the crushing-rollers; and my invention consists of the improvements in the construction of the feed mechanism, which will be hereinafter fully set 25 forth, and pointed out in the claims.

In the accompanying drawings, Figure 1 is a vertical section of a double-roller mill provided with my improved feed device. Fig. 2 30 is a horizontal section in line *xx*, Fig. 1. Fig. 3 is a vertical section in line *yy*, Fig. 1. Fig. 4 is a side elevation, partly in section, of my improved feed mechanism on an enlarged scale.

Like letters of reference refer to like parts in the several figures.

A A represent two pairs of crushing or grinding rollers, arranged in a casing, B, and supported in bearings *b*, secured to a stationary frame, B', in a well-known manner.

C C represent the feed-hoppers, of ordinary construction, arranged above the rollers A A, and divided by a partition, *c*, which terminates at its lower end in two downwardly-dipping inclined boards, *c'*.

D represents the outer inclined walls of the feed-hoppers, and E the feed-gates, arranged at the lower ends of the outer walls, D, for regulating the escape of the material from the 50 feed-hoppers. The feed-gates E are automatically adjusted by hinged boards *e*, arranged

in the feed-hoppers, and connected with the feed-gates by rods *f*, which are attached to the feed-gates and rest against arms *e'*, projecting rearwardly from the feed-gates. The latter 55 are provided with arms *e*, which are provided with pivots extending through the side walls of the feed-hoppers. *e* are arms secured to the outer ends of these pivots, and *e'* are springs which are secured to the outer side of 60 the feed-hoppers in such manner that they are compressed or strained by the opening movement of the feed-gates. These springs are provided with adjusting-nuts, whereby their tension can be regulated. The pressure of 65 the material in the feed-hopper upon the hinged board *e* tends to open the feed-gate, and this movement is resisted by the spring, so that the opening of the feed-gate is proportionate to the quantity of material contained 70 in the feed-hopper.

F represents a movable board or plate arranged below the discharge-openings of the feed-hoppers C, immediately underneath the lower ends of the inclined walls *c'* and the 75 feed-gates E, so that the material passes from the discharge-openings of the feed-hoppers directly upon the plate F, and is to a certain extent supported by the latter. *g* are agitating-pins secured to the upper side of the plate F, 80 and projecting upwardly into the discharge-openings of the feed-hoppers for stirring and disintegrating the material in the throats of the hoppers. The outer edges of the plate F are beveled or inclined, as shown at *h*, and connected with sieves H, which extend outwardly beyond the outer roller of each pair of grinding-rollers. The meshes of the sieves H are made so coarse that they will permit all material which is to be reduced to pass through the 90 sieves and between the rollers; and will only carry beyond the rollers nails and other hard and large substances which may accidentally become mixed with the material as it is conveyed from one machine to another in the mill. 95 The plate F and sieves H are attached to a frame, I, which is supported by spring bars or links *i*, secured with their lower ends to the inner sides of the casing B. The frame I receives a reciprocating motion parallel with the longitudinal axes of the rollers by an eccentric, *j*, which is mounted upon a counter-shaft, *j'*, and 100

connected with the frame I by a rod, K. The shaft j' is unsupported in bearings L, and rotated from one of the roller-shafts by an endless belt, m, running around a pulley, M, on the shaft j'.

5 The plate F is provided on its upper side with ribs n, arranged on the inner sides of the inclined walls c', to prevent the material from flowing backwardly on the plate F. The material contained in the throats of the feed-hoppers C rests upon the plate F, and is constantly agitated and disintegrated by the vibratory motion of the agitating-pins g, and evenly distributed over the entire width of the plate F, underneath the discharge-openings of the feed-hoppers. The material is further distributed as it passes over the edges h of the plate F and the sieves H, so that the feed is rendered uniform over the entire length of the rollers, and the clogging or accumulation of material upon 15 any part of the feed mechanism is entirely prevented. When only one pair of rollers is employed in the reduction-machine, the plate F and frame I need not extend beyond the rib n on the rear side of the feed-hopper, the feed mechanism in this case being composed of 20 only one-half the parts shown in Fig. 1.

The automatic feed-gates are adjustable toward and from the plate F, and thereby regulate the quantity of material which is discharged from the feed hoppers.

30 I claim as my invention—

1. The combination, with the feed-hopper, of a board or plate arranged below the dis-

charge-opening of the feed-hopper to receive the material therefrom, agitating-pins secured to said board or plate and projecting into the throat of the feed-hopper, mechanism whereby a shaking motion is imparted to said board or plate, and a feed-gate adjustable toward and from said board or plate, substantially as set forth.

2. The combination, with the grinding mechanism, of a feed-hopper, a board or plate arranged below the discharge-opening of the feed-hopper to receive the material therefrom, 45 agitating-pins secured to said board or plate and projecting into the throat of the feed-hopper, mechanism whereby a shaking motion is imparted to said board or plate, and a screen attached to said board or plate and adapted to 50 exclude the coarse material from the grinding mechanism, substantially as set forth.

3. The combination, with the feed-hopper, of a board or plate arranged below the discharge-opening of the feed-hopper to receive 55 the material therefrom, agitating-pins secured to said board or plate and projecting into the throat of the feed-hopper, mechanism whereby a shaking motion is imparted to said board or plate, and feed-gate capable of automatic 60 adjustment toward and from said board or plate, substantially as set forth.

NOAH W. HOLT.
